UNITED STATES PATENT OFFICE.

WALTER F. BAILEY, OF LOS ANGELES, CALIFORNIA, ASSIGNOR OF ONE-HALF TO
GEORGE A. CADWALLADER, OF LOS ANGELES, CALIFORNIA.

COASTER.

1,272,761.

Specification of Letters Patent. Patented July 16, 1918.

Application filed May 31, 1916. Serial No. 100,894.

To all whom it may concern:

Be it known that I, WALTER F. BAILEY, a citizen of the United States, residing at Los Angeles, in the county of Los Angeles and 5 State of California, have invented new and useful Improvements in Coasters, of which the following is a specification.

This invention relates to a coaster and particularly pertains to a small portable 10 vehicle used by children for coasting upon grades and to convey them from place to place.

It is an object of this invention to provide a light, portable vehicle upon which a 15 person may stand and by which he may be carried.

Another object is to provide treadle means whereby the device may be set in motion by the movement of the feet when it is not moving on a grade.

Another object is to provide means whereby the movement of the foot treadles will act to impel the vehicle in a forward direction irrespective of which treadle is moved.

25 It is another object to provide a propelling mechanism in connection with the treadle members which will run idle and not interfere with the forward movement of the vehicle when the foot treadles are held 30 against movement and thus allow the vehicle to coast when sufficient momentum has been obtained.

It is an object of this invention to provide a simple clutch mechanism which is 35 operated in connection with the foot treadles to rotate the driving gear of the vehicle and which will run idle when the driving gear is rotated by other forces than that of the propelling mechanism.

40 Another object of this invention is to provide a suitable steering means which also forms a substantial member for steadyng the rider standing upon the vehicle.

Another object is to provide a simple 45 power transmission member adapted to connect the foot treadles with the driving clutch, said member being simple in design and not easily made inoperative.

It is a further object to provide a coaster 50 which is substantial in its construction and of few simply constructed movable parts which may be readily maintained in an operative condition by the ordinary youth.

Other objects will appear hereinafter.

The invention is illustrated in the accompanying drawings in which:

Figure 1 is a view in side elevation illustrating the device as assembled for use and showing the steering column as broken away for the sake of convenience.

Fig. 2 is a view in plan of the coaster as shown in Fig. 1 and illustrates the relation between the foot treadles and the power transmission mechanism of the device.

Fig. 3 is a view in side elevation with 65 parts shown in vertical section to illustrate the clutch arrangement of the rear axle.

Fig. 4 is a view in vertical section through the power transmission and the driving axle of the coaster as seen on the line 4—4 of 70 Fig. 3 and in the direction indicated by the arrows.

Referring to the drawings more particularly, 10 indicates a horizontally disposed floor board beneath which is a running gear 75 comprising a single front steering wheel 11 and a pair of oppositely arranged driving wheels 12 and 13 positioned in a suitable manner, to be hereafter described, beneath the rear end of the floor board. The front 80 steering wheel is provided with a wheel fork composed of a pair of vertically extending fork members 14 and 15 which are secured to a steering post 16 by means of suitable screws 17. The steering post 16 is here 85 shown as constructed of wood and extending upwardly a considerable distance above the line of the floor 10. A pair of handle bars 18 are rigidly secured adjacent the upper terminating end of the steering column and 90 provide means for the steering wheel 11 to be turned upon its pivot pin 19 which is secured to the steering column by means of a U-shaped bracket 20. The bracket 20 has bearing lugs 21 and 22 formed at its ends 95 and in vertical relation to each other. The pivot pin 19 secures the bracket and its steering gear to the floor board of the vehicle by means of a lower bracket member 23 suitably fastened to the floor board and an 100 upper bracket and reinforcing member 24 which is secured over the top of a treadle pivot block 25. The member 24 extends diagonally downward to the floor board where it is secured by a suitable bolt 26.

105 The treadle pivot block is secured by means of bolts 27 to the forward end of the floor 10 and extends upwardly in a vertical

manner. A treadle pivot pin 28 is horizontally disposed and positioned through the upper end of the pivot block and is adapted to engage the pivot ends 29 and 30 5 of the treadles 31 and 32. The pivot ends 29 and 30 are a part of treadle frame members 33 and 34 arcuately formed to sweep downwardly and then continue throughout a single plane. Their rear ends 35 and 36 10 are turned at right angles to the body portion in order to suitably engage a power transmission member which will hereafter be described. A pair of treadle foot-boards 37 and 38 are secured by suitable screws 39 15 upon the top of the treadle frame and are of suitable shape to properly accommodate the feet of the rider, and allow him to stand thereupon while operating and riding upon the coaster.

Reference being had to Fig. 4 of the drawing, it will be observed that the rear driving wheels 12 and 13 are mounted to rotate with the driving axle 40 suitably secured to the footboard 10 by means of a bearing member 41 provided with a pair of oppositely disposed downwardly extending axle supports 42 and 43. The bearing member 41 is mounted upon the foot-board by bolts 44. The axle 40 extends horizontally between the rear wheels 12 and 13 and is formed at its outer ends with threaded portions 45 adapted to be engaged by suitable nuts which rigidly hold the wheels against shoulders 46 of the cylindrical axle ends 47 and 48. The 30 axle portions 47 and 48 extend to a point adjacent the center of the axle where a ratchet member 49 of an enlarged diameter is mounted. The ratchet member is formed with a series of longitudinally extending teeth member 50 which have a radial face and a tapering back leading to the lowermost edge of the tooth face adjacent. It will be noted that the straight radial faces are disposed toward the rear of the coaster as they 35 pass around and over their axial point. The ratchet member 49 is of sufficient width to be partially encompassed by the enlarged portion of a pair of driving sleeves 51 and 52 which are adapted to bear upon the cylindrical axle portions 47 and 48 and rotate therearound. A pair of pawls 53 and 54 are pivotally secured within the enlarged portions of each of the sleeves and are adapted to normally abut against the radial faces of the 40 teeth 50 being there held by means of spring members 55. It will thus be seen that when either of the sleeves is rotated in the direction indicated by the arrow—a—the ratchet teeth will be engaged and the axle with its 45 driving wheels will be rotated to move the vehicle in a forward direction.

As a means of transmitting the movement of the foot treadles 37 and 38 to the rear axle and thereby rotate it, an endless cable 56 has been provided which is suitably

clamped against the rear terminating ends of the treadle frames by clamping straps 57 and 58 which are held by bolts 59. The endless cable 56 is provided with a pair of horizontally disposed grooved idler pulleys 60 and 61 rotatably mounted at the upper end and within a U-shaped transmission case 62 which extends vertically from the foot-board 10 and is there secured by means of bolts 63.

The endless cable 56 is led downwardly 75 from the opposite outer sides of the pulleys 60 and 61 and is led around the sleeve members 51 and 52 which are rotatably mounted upon the driving axle. After having been led around the sleeves a sufficient number of turns to correspond in circumferential length to the treadle movement, the cable is passed through clamping bosses 64 and there held by means of set screws 66. Another portion of the cable is then led around the 80 sleeve and upwardly over a centrally disposed idler wheel 67. Examination of the driving cable 56 as particularly shown in Fig. 4 of the drawing, will disclose the fact that the cable is positioned and arranged in 85 relation to its treadle members and the rear axle so that an up and down movement of either treadle will act to rotate one of the sleeves in an advanced direction and thereby cause its pawl members to engage the driving 90 ratchet and rotate the driving axle.

In view of the preceding description, the operation of the device is evident as it may readily be seen that when the rider mounts the treadle members and alternately actuates them by his feet, the transmitting cable 56 will act to rotate the driving axle by means of its sleeve and engaging pawls. When the device is to be used, it is not necessary for either treadle to be first depressed, but a 105 downward pressure upon either treadle will act to engage the driving ratchet and advance the vehicle. In case the driver desires to stand idly upon the treadles and coast, the two sleeve members 51 and 52 will 110 be rigidly held and allow the axle to rotate without engaging the ratchet with the driving pawls.

It will thus be seen that a coaster is here provided which may be readily guided in 115 any desired path of travel and may be actuated with or without the use of the power transmission mechanism. It will further be observed that the device is provided with simple propelling means which may be operated without considerable skill and which 120 will act to propel the vehicle or allow it to coast at the will of the driver.

I claim:

In a coaster, a horizontally disposed floor 125 board, a front steering wheel pivotally secured adjacent one end of said floor board, a driving axle rotatably mounted beneath the opposite end of the floor, a pair of driving wheels secured to the driving axle at its 130

opposite outer ends, a ratchet member fixedly mounted upon said driving axle, rotatable clutch sleeves mounted upon opposite ends of said driving axle, engaging dogs pivotally mounted within the rotatable sleeves and adapted to engage the ratchet member, means for holding said dogs in engagement with the ratchet, a pair of vertically moving treadle members pivoted above the floor board, means for steering the coaster and suitably steadyng the rider upon the treadles,

and transmission means connecting the treadles and the rotatable clutch sleeves whereby the downward movement of either treadle will act to rotate said sleeves and 15 thereby impart driving motion to the axle member to propel the vehicle in a forward direction.

In testimony whereof I have signed my name to this specification.

WALTER F. BAILEY.

Copies of this patent may be obtained for five cents each, by addressing the "Commissioner of Patents, Washington, D. C."
